US00D817068S

(12) **United States Design Patent** (10) **Patent No.:** **US D817,068 S**
(45) **Date of Patent:** **** May 8, 2018**

(54) **COOKER**

(71) Applicant: **Eades Appliance Technology, LLC**, Incline Village, NV (US)

(72) Inventors: **Michael R. Eades**, Incline Village, NV (US); **Mary Dan Eades**, Incline Village, NV (US); **Daniel J. Eades**, Santa Barbara, CA (US); **Ted M. Eades**, Dallas, TX (US); **Davin Stowell**, New York, NY (US); **Joern Vicari**, San Francisco, CA (US); **Chris Xydis**, Incline Village, NV (US)

(73) Assignee: **Eades Appliance Technology, LLC**, Incline Village, NV (US)

(**) Term: **15 Years**

(21) Appl. No.: **29/553,543**

(22) Filed: **Feb. 2, 2016**

(51) LOC (11) Cl. **07-02**

(52) U.S. Cl.

USPC **D7/354**

(57) **CLAIM**

The ornamental design for a cooker, as shown and described.

DESCRIPTION

FIG. 1 is a perspective view of a cooker in accordance with the present design;

FIG. 2 is a right side view of the cooker illustrated in FIG. 1;

FIG. 3 is a left side view of the cooker illustrated in FIG. 1;

FIG. 4 is a front view of the cooker illustrated in FIG. 1;

FIG. 5 is a rear view of the cooker illustrated in FIG. 1;

FIG. 6 is a top view of the cooker illustrated in FIG. 1; and,

FIG. 7 is a bottom view of the cooker illustrated in FIG. 1.

Shading and stippling in the figures depicts contrast in material, color, or lighted and nonlighted detail.

1 Claim, 7 Drawing Sheets
